SUN LAMP

Charles E. Branick, Fargo, N. Dak.

Application July 5, 1957, Serial No. 46,845

Term of patent 14 years

(Cl. D48—20)

Fig. 1 is a view in front elevation of a sun lamp showing my new design with the electric cord and plug omitted for convenience of illustration; and

Fig. 2 is a perspective view as seen from the rear and one side and on a slightly enlarged scale.

The dominant features of my design reside in those portions shown in full lines.

I claim:

The ornamental design for a sun lamp, as shown and described.
